(57) **CLAIM**

The ornamental design for a lace fabric, as shown and described.

DESCRIPTION

FIG. 1 is a front side view of a lace fabric showing my new design;

FIG. 2 is a back side view thereof;

FIG. 3 is a front perspective view thereof;

FIG. 4 is an enlarged front view thereof showing a repeating unit of the claimed design; and,

FIG. 5 is an enlarged front view thereof showing a portion of a repeating unit of the claimed design.

A specific or particular length of the subject article forms no part of the claimed design.

1 Claim, 5 Drawing Sheets
